DESK CALENDAR

John F. Bannon, Providence, R. I., assignor to
 Defiance Sales Corporation, New York, N. Y.,
 a corporation of New York

Application April 2, 1941, Serial No. 386,413

6 Claims. (Cl. 40—120)

My invention relates to a desk calendar and memorandum pad. In desk calendars and memorandum pads heretofore used a pad of memorandum sheets having respective calendar dates was mounted on a base and secured thereon by a binder plate overlying part of the pad and posts extending from the binder plate into the base. As successive sheets of the pad were used they could be torn away at the edge of the binder plate and when a number of sheets had been torn away the binder plate could be released the stubs removed and the binder plate replaced on the unused sheets to maintain a neat appearance.

In my present invention I provide a binder plate having a window to enable a calendar for the entire year, or other data, to be visible therethrough while at the same time providing a transparent sheet to protect the stubs carrying the yearly calendar from becoming dusty or soiled.

My invention also provides means whereby the binder plate may be readily removed and secured in position and presents a neat appearance.

The various features of my invention are illustrated by way of example in the accompanying drawing in which Fig. 1 is a plan view of a calendar or memorandum embodying a preferred form of the invention. Fig. 2 is a side view of the calendar or memorandum shown in Fig. 1, part of the base being broken away to show the mounting of the binding post. Fig. 3 is a bottom plan view of the binding plate. Figs. 4, 5 and 6 are sections taken respectively on the lines 4—4 and 5—5 of Fig. 1 and 6—6 of Fig. 4.

In the embodiment of the invention shown in the accompanying drawing, a calendar pad is shown at 10 which may be of any suitable type as, for example, one having a sheet for each day of the year. In the embodiment shown each sheet of the pad has a monthly calendar part 11 and a memorandum part 12 and a part 13 containing a calendar for the entire year. At the opposite edges of the part 13 the pad is provided with a pair of openings or passages 14.

The pad 10 is mounted or supported on a hollow base 15 having a supporting plate 16 slightly inclined from the horizontal and provided with a pair of spaced openings 17 directly underlying the openings 14 of the pad 10 when the pad is in proper position on the base. The pad is held in position on the base 15 by means of a binder plate 18 overlying the part 13 of the pad and a pair of threaded posts 19 extend through suitably spaced openings in the binder plate 18

and through the openings 14 into the threaded opening 17 of the base. The plate 16 is raised sufficiently to permit the lower ends of the posts 19 to extend below it a considerable distance.

5 The binder plate 18 is provided with a window 20 overlying the year calendar of the part 13 so that the calendar for the year may be readily seen therethrough. To protect the calendar-carrying part 13 which remains under the binder plate as a stub when the memorandum and daily calendar sheet is torn away, a transparent sheet 21 of suitable material, such as Celluloid, is mounted on the undersurface of the binder plate 18 in such manner as to span the window 20. 10 The transparent sheet 21 is held in position against the undersurface of the binder plate 18 by means of a pair of securing or holding plates 22, one at each end of the window 20. For this purpose the transparent sheet is notched at its 15 opposite ends as at 23 overlying the openings 14 of the pad 10 so as to permit the posts 19 to extend therethrough. A pair of internally threaded heads or nuts 24 is mounted on the upper surface of the binder plate 18, one above each of the 20 openings 14 and posts 19, and has a neck that extends downwardly through a suitable opening in the binder plate 18 and respective holding plate 22 as shown in Fig. 5 so that it holds the holding plate 22 tightly against the lower surface of the binding plate 18 and clamps the ends of the transparent sheet 21 firmly against the binder plate. The neck of the heads or nuts 24 is rotatably mounted in the openings in the binder plate and holding plates 22 so that it may rotate 25 and thus be threaded onto the post 19 or, reversely, free of its respective post.

To enable each head or nut 24 to be screwed tightly onto the plate 18 with a minimum of turning the post 19 has a reduced extension 25 30 which readily enters the opening in the head or nut and engages the top thereof when a few threads of the post are engaged by the nut.

The binder plate 18 is downturned at its edges in such manner that the upper and side flanges 26 and 27 cover the upper parts of the top and sides of the stub portion 13 of the pad and the front flange 28 which is narrower bears tightly 35 onto the upper surface of the pad.

The edges of the window 20 are also downturned as at 29 to form a neat appearance and clamp the transparent sheet 21 tightly onto the stub portion of the pad.

In assembling the calendar or memorandum the pad 10 is placed on the base 15 with the 55 openings 14 of the pad overlying the opening 17

of the base and threading about the posts 19. The cover or binder plate 18 is then placed in position with its top and sides 26 and 27 against the top and side edges of the stub portion of the pad whereupon the heads or nuts 24 will overlie the posts 19. By rotating the heads or nuts 24 they thread onto the posts 19 engaging a few of the threads until the upper end of the extension 25 abuts the inner surface of the head, whereupon further turning threads the posts 19 downwardly through the opening 17 until the plate 18 clamps the pad tightly onto the base whereupon further turning of the heads or nuts 24 is prevented.

In using the pad it is customary to tear off each sheet as it is used leaving the stubs of the sheet caught below the binder plate 18. When a considerable thickness of stubs has thus been left under the plate 18, it is desirable to lift the plate and remove the stubs and then clamp the binder plate onto the unused part of the pad. To do this it is only necessary to unscrew the head or nut 24, lift the binder plate 18 and remove the stubs, then the binder plate may be placed in position, each head 24 threaded onto the post 19 until the latter engages the upper part of the head whereupon it will screw downwardly in the base 16 until the binder plate is firmly secured in its proper position. This may be repeated until the pad is completely used.

It will be apparent that at all times a calendar for the entire year is visible through the window 20 and is protected from dust by the transparent sheet 21. The mounting of the nuts 24 leaves a smooth unbroken surface on which there is no opportunity at the heads for the collection of dust or dirt. Inasmuch as the heads are secured to the base plate they cannot become lost, and are properly aligned with the posts when the binding plate is put in position on the stub. The reduced portions of the post 25 aid in the positioning of the heads and binding plate as they are sufficiently small to permit ready insertion in the heads or nuts and facilitate the centering of the nuts or heads in the proper position on the posts.

What I claim is:

1. A desk calendar of the type described which comprises a base having a pair of spaced threaded openings, a calendar pad on said base having openings overlying those of said base, a binding plate on said pad having openings overlying those of said pad, threaded posts one extending through each of said openings in said pad and binding plate and threaded into and through the openings in said base, said binding plate having a window, a transparent sheet secured to the underside of said binding plate and spanning said window and a pair of heads each recessed and threaded internally and engaging the threads on the upper end of a respectively threaded post and extending over the upper end of said post to abut it when threaded downwardly thereon and having a neck extending through and rotatably

engaged in the respective opening of said binding plate.

2. The article of claim 1 in which the upper end of said post is reduced to pass freely into the upper part of the recess in said head.

3. A desk calendar of the type described which comprises a base having a pair of spaced threaded openings, a calendar pad on said base having openings overlying those of said base, a binding plate on said pad having openings overlying those of said pad, threaded posts one extending through each of said openings in said pad and binding plate and threaded into the openings in said base, said binding plate having a window, a pair of holding plates below said binding plate beyond the opposite ends of said window, a transparent sheet secured to the underside of said binding plate spanning said window and engaged between said binding plate and said holding plates, a pair of internally threaded heads beyond the ends of said window each having a neck portion extending through said binding plate and said holding plate and rotatable therein to hold said plates in close engagement and to screw onto said posts.

4. In combination, a binding plate for desk pads, said plate having a window, holding plates below said binding plate beyond the opposite ends of said window, a pair of internally threaded heads rotatably mounted on said binding plate near the edges thereof and engaging said holding plates and a transparent sheet below said binding plate spanning said window and engaged between said binding plate and said holding plates.

5. In combination, a binding plate for desk pads, said plate having a window, holding plates below said binding plate beyond the opposite ends of said window, said holding plate and said binding plate having overlying openings, a pair of internally threaded heads having necks extending downwardly through said openings and rotatably engaging said holding plate and said binding plate and a transparent sheet below said binding plate spanning said window and engaged between said binding plate and said holding plates.

6. A desk calendar of the type described which comprises a base having a pair of spaced threaded openings, a calendar pad on said base having openings overlying those of said base, a binding plate on said pad having openings overlying those of said pad, threaded posts one extending through each of said openings in said pad and binding plate and threaded into and through the openings in said base, and a pair of heads having threaded recesses receiving and engaging the upper end of a respectively threaded post and abutting the upper end of said post when screwed downwardly thereon and having a neck extending through and rotatably engaged in the respective opening of said binding plate.

JOHN F. BANNON.
